(57) **CLAIM**

The ornamental design for a mobile phone case, as shown and described.

DESCRIPTION

FIG. 1 is a front, right-side, and bottom perspective view of a mobile phone case showing my new design;

FIG. 2 is a rear, left-side, and top perspective view thereof;

FIG. 3 is a front elevational view thereof;

FIG. 4 is a rear devotional view thereof;

FIG. 5 is a left side view thereof;

FIG. 6 is a right side view thereof;

FIG. 7 is a top plan view thereof;

FIG. 8 is a bottom plan view thereof;

FIG. 9 is a front, left-side, and bottom perspective view thereof showing the integral bottom dust plug in an open position;

FIG. 10 is an exploded rear, right-side, and top perspective view thereof showing the two components of the case separated for clarity of disclosure;

FIG. 11 is an enlarged view of area 11 shown in FIG. 1; and, FIG. 12 is an enlarged view of area 12 shown in FIG. 2.

The broken lines depict portions of the mobile phone case that form no part of the claimed design.

The dot-dash broken line circles in FIGS. 1-2 and 11-12 and the dot-dash lead lines extending from the dot-dash broken line circles in FIGS. 1-2 form no part of the claimed design and designate portions of the mobile phone case that are part of the claimed design and that are shown on an enlarged scale in FIGS. 11-12. The dashed broken lines throughout the drawing figures form no part of the claimed design and depict portions of the mobile phone case that form no part of the claimed design.

1 Claim, 12 Drawing Sheets
